RADIO CONTROLLED MINE

John Hays Hammond, Jr., Gloucester, Mass.,
assignor to Radio Corporation of America

Application September 26, 1942, Serial No. 459,787

8 Claims. (Cl. 102—8)

1

This invention relates to mines which detonate when approached by moving objects and has for an object to provide means responsive to radiant energy signals for rendering the detonating mechanism inoperative.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Figure 1 illustrates schematically the radio controlled mine in relation to an approaching tank;

Figure 2 shows diagrammatically the circuits employed in one type of radio transmitter on the tank; and

Figure 3 depicts diagrammatically the circuits employed in one type of radio receiver at the mine. Like reference characters denote like parts in the several figures of the drawings.

In the following description and in the claims parts will be identified by specific terms for convenience, but they are intended to be as generic in their application to similar parts as the art will permit.

Referring to the accompanying drawings and more particularly to Figure 1 a mine 11 is shown as buried in the ground. The mine 11 comprises an explosive charge 12, a detonator 13 for exploding said charge, a detonating circuit 14 and a radio receiver 15. The detonating circuit 14 may be of any well known construction, such for example, as a magnetically operated device which is connected to a relay 16 and which is operated by the approach of a metallic object such as a tank 17. The relay 16 is in circuit with the detonator 13, a battery 18 and relay 19 the contacts of which are normally closed but are arranged to be opened by the radio receiver 15.

Transmitter

In the tank 17 is mounted a transmitter 21 which comprises three tone generators 22, 23 and 24, a modulator 25, a master oscillator 26, a buffer doubler 27 and a power amplifier 28. The tone generators 22, 23 and 24 are of well known construction and generate three distinct frequencies which for example may be of 600, 800 and 1100 cycles respectively. The difference between any

2

two of the frequencies preferably is not the same as the difference between any other two frequencies, and they are preferably within a single octave. If desired these frequencies may be super or subaudible.

The three tone generators 22, 23 and 24 each comprise a triode tube 75 the cathode of which is connected to ground thru a cathode resistor and a condenser 76. The plate circuit of the tube 75 includes an oscillatory circuit 77 with a feed back 78 to the grid. From taps on the feed back coils 78 energy is fed into the combining circuit thru mixing resistors 79. Plate feed resistors 80 are provided and are adjusted so that approximately the same voltage to the common circuit results from the three oscillators 22, 23 and 24.

The combining circuit 25 comprises a triode 81 with cathode biased by means of the resistor-condenser circuit 32. The grid of the tube 81 is connected to the contact of a switch 83, the blade of which is ground. The plate circuit of the tube 81 is coupled to the grids of two modulator tubes 84 and 85 by means of a band pass filter 86 which transmits the three frequencies produced by the three tone generators 22, 23 and 24. The cathodes of the tubes 84 and 85 are biased positively with respect to ground by the resistor 87. The plates of the tubes 84 and 85 are connected to the primary winding of a modulation transformer 88 the center tap of which is polarized positively with respect to ground by plate battery 89.

The frequency of radiooscillation of the oscillator 26 is determined by a piezo electric crystal 90a connected between the control grid of a pentode 90 and ground and shunted by radio frequency choke 91 and resistor 92. The cathode of tube 90 is biased positively to ground by cathode resistor and condenser 93 and is also connected to the third grid. The positive end of a battery 94 is connected to the second grid of the tube 90 and thru a circuit 95, tuned to the crystal frequency, to the plate of tube 90. The plate is connected to the control grid by condenser 96, which may be represented by the internal capacity of the tube 90.

A tap on the coil of the tuned circuit 95 is connected to the control grid of a doubler tube 97 by coupling condenser 98. The control grid of tube 97 is conductively connected to ground thru choke 99 and resistor 100, which is shunted by condenser 101. The cathode of tube 97 is connected to the third grid and thru a cathode resistor and condenser 102 to ground. The positive side of a plate supply battery 103 is connected to the second grid of the tube 97 and thru

a circuit 104, tuned to double the crystal frequency, to the plate of the tube 87.

A tap on the coil of the tuned circuit 104 is connected to the control grid of a pentode 105 by coupling condenser 106. The control grid of the tube 105 is conductively connected to ground thru a choke 107 and resistor 108, which is shunted by condenser 109. The cathode of tube 105 is connected to the third grid and thru a cathode resistor and condenser 111 to ground. The second grid of tube 105 is connected thru a resistor 112 to the positive side of a plate battery 113 the negative side of which is grounded. The second grid is also connected thru a resistor 114 to the contact of switch 110 the blade of which is connected to ground. The switches 83 and 110 may be interconnected so as to be operated in unison.

The positive side of the plate battery 113 is connected thru the secondary of the modulation transformer 88, radio frequency choke 115 and oscillatory circuit 116, tuned to double the crystal frequency, to the plate of the tube 105. A radio frequency bypass condenser 117 is connected from the positive side of battery 113 to the junction of the choke 115 and circuit 116. The oscillatory circuit 116 is coupled to a coil 118 one end of which is grounded and the other end connected thru a loading coil 119 and tuning condenser 121 to an antenna 122.

In the operation of the transmitter depicted in Figure 2 high frequency energy will be generated by the master oscillator 26 the frequency of which will be determined and held constant by the piezo-electric crystal 90a. The frequency of this energy will be doubled by the buffer doubler 27 and will be impressed upon the power amplifier 28. With the switch 110 closed the power amplifier 28 will be inoperative so that no energy will be radiated by the antenna 122.

The three tone generators 22, 23 and 24 each generate a different frequency, which for example may be 600, 800 and 1100 cycles respectively. When the switch 83 is closed the tone generators 22, 23 and 24 do not affect the modulator 25. When the switch 83 is open, however, energy of 600, 800 and 1100 cycles is impressed upon the modulator 25, so that modulating energy is impressed upon the plate of the tube 105. When the switch 110 is opened the power amplifier 28 becomes operative and causes high frequency energy, modulated at 600, 800 and 1100 cycles, to be radiated from the antenna 122. The switches 83 and 110 may be interconnected so that the two operations occur simultaneously or switch 110 may be opened to produce radiations prior to opening switch 83 to cause modulation of the radiations.

Receiver

Referring to Figure 3 a receiver is shown for receiving the energy radiated by the antenna 122 of the transmitter. This receiver comprises a radio frequency amplifier 41 connected to an antenna 42, a detector and audio amplifier 43, a plurality of tuned circuits 44, combining and amplifying circuits 45, two rectifying and detecting circuits 46 and 47 and a relay tube circuit 48.

The antenna 42 is connected thru a condenser 131 to a tap on a radio tuning coil 132 one terminal of which is connected to the AVC line and the other to the grid of a radio amplifier tube 133. A condenser 134 is connected between the AVC line and ground and a tuning condenser 135 is connected between the control grid of tube 133 and ground. The cathode of tube 133 is con-

nected to the third grid and to ground. The screen grid of tube 133 is connected to the positive side of a battery 136 and to the negative side of a battery 137, the positive side of which is connected thru the primary circuit of a tuned transformer 138 to the plate of tube 133.

The secondary circuit of the transformer 138 is connected to the diode plate of detector amplifier tube 141 and to the AVC line. The cathode 10 of the tube 141 is connected thru a cathode resistor and condenser 142 to ground and also thru tapped resistor 143, shunted by condenser 144, to the AVC line. The grid is connected thru condenser 145 to the tap of resistor 143 and is also connected thru a resistor 146 to ground. The plate of tube 141 is connected thru three tuned circuits 53, 52 and 51 to the positive side of a battery 147 the other side of which is grounded.

The three tuned circuits 51, 52 and 53 are tuned to the three frequencies of the three tone generators 22, 23 and 24 of the transmitter depicted in Figure 2. These frequencies for example may be 600, 800 and 1100 cycles respectively. The tuned circuit 51 is loosely coupled to a secondary tuned circuit 54 which is tuned to 600 cycles, the tuned circuit 52 is loosely coupled to two secondary tuned circuits 55 and 56 both of which are tuned to 800 cycles and the tuned circuit 53 is loosely coupled to a secondary tuned circuit 57 which is tuned to 1100 cycles.

The tuned circuits 54 and 57 are connected thru rectifiers 58 and 59 to two tuned circuits 61 and 62 which are tuned to frequencies of 200 and 300 cycles respectively. The combining and amplifying circuits 45 comprise two amplifiers 63 and 64 the output circuits of which are connected to the primary of a transformer 65 both the primary and secondary of which are broadly tuned to 200 to 300 cycles. The secondary of the transformer 65 is connected to the rectifying and detecting circuit 48. This circuit includes a rectifier 66 and the primary of a transformer 67 which is tuned to a frequency of 100 cycles by means of a condenser 67a.

The secondary of the transformer 67 is tuned to 100 cycles by means of a condenser 70 and is connected to the rectifying and detecting circuit 47 which includes a rectifier 68 and a resistor 69. The rectifying circuit 47 is connected thru a time delay circuit 71 to the relay tube circuit 48 the output circuit of which includes the winding of the relay 18.

In the operation of the receiver shown in Figure 3, the radio signal is received by the antenna 42 and is amplified by the radiofrequency amplifier 41. The amplified signal is detected and further amplified by the detector and audio amplifier 43. The output of the audio amplifier 43 is fed to the three tuned circuits 51, 52 and 53 where the three frequencies of 600, 800 and 1100 cycles are selected by the three circuits 51, 52 and 53 respectfully.

Currents of 600 cycles are induced in the tuned circuit 54 as the circuits 51 and 54 are sufficiently loosely coupled so that they transmit 600 cycles and not the other two frequencies of 800 and 1100 cycles. Currents of 800 cycles are induced in the tuned circuit 55 as the circuits 52 and 55 are sufficiently loosely coupled so that they transmit 800 cycles and not the other two frequencies. The currents of 600 and 800 cycles are detected by the rectifier 58 and a current having their difference frequency, namely 200 cycles, is induced in the tuned circuit 61 which is tuned to

this frequency. In a similar manner, currents of 800 and 1100 cycles are induced in the tuned circuits 56 and 57 respectively. These currents are detected by the rectifier 59 and a current having their difference frequency, namely 300 cycles is induced in the tuned circuit 62 which is tuned to this frequency.

The currents of 200 and 300 cycles are amplified by the amplifiers 63 and 64 respectively, and are combined in the tuned circuit which includes the primary of the transformer 65, which is sufficiently closely coupled so that the transformer as a whole transmits 200 and 300 cycles. Currents of 200 and 300 cycles are induced in the secondary of the transformer 65 and are detected by the rectifier 66 and a current having their difference frequency, namely 100 cycles, is fed to the tuned circuit which includes the primary of the transformer 67, which is tuned to this frequency.

Current of 100 cycles is induced in the secondary of the transformer 67, is rectified by the rectifier 68 and flows thru the resistor 69 in the direction of the arrow. Under normal conditions the relay tube 48 operates with no bias on the grid so that a steady current flows thru the winding of the relay 19 keeping it energized. When, however, current flows thru the resistor 69 in the direction of the arrow a negative bias will be applied to the grid of the tube 48 thus decreasing the current flowing in the winding of the relay 19 which will cause this relay to open.

Referring to Figure 1 it is seen that under normal conditions when no radio signal is received by the receiver 15 the relay 19 will be closed and the relay 16 open. If a tank or other object approaches the mine 11 the detonating circuit 14 will be activated causing the relay 16 to close. This will complete a circuit from the battery 18 thru the relays 19 and 16 to the detonator 13 which will be detonated causing the firing of the explosive charge 12.

If, however, the tank 17 is transmitting a radio signal in a manner described in connection with Figure 2 the receiver 15 will be operated to cause the relay 19 to be deenergized, as described in connection with Figure 3. This will make the detonating circuit inoperative so that when the tank passes over the mine 11 and causes the energization of the relay 16 the explosive charge will not be fired and the tank will pass safely over the mine. If the batteries of the receiver 15 become run down the relay 19 will become deenergized thus making the detonating circuit inoperative and the mine will become "dead."

It is thus seen that a radio controlled mine is provided which will explode by the passage of any tank or other metal object, which is not transmitting a particular type of radio signal, but which will be made "dead" or inoperative when a tank transmitting the particular type of radio signal passes over it. The triple modulation and various selective circuits reduce the possibility of the enemy finding the correct combination for operating the receiver.

It is to be understood that the system may be so designed that it operates in the opposite sense. That is the radio receiver 15 may be so constructed that normally, in the absence of any radio signal being received by the antenna 42, the relay 19 will be de-energized and its contact open so that the mine is "dead." On receipt of the proper signal, however, the relay 19 will be energized and its contact closed so that the mine then becomes "alive."

In this way it is possible to have a mine field normally inactive, so that it may be crossed by tanks without danger. On the approach of the enemy, however, the appropriate radio signal is sent out and the relays 19 of all the mines in the field are energized, so that the whole mine field becomes active and any tank passing over a mine will cause its detonation.

Although only a few of the various forms in which this invention may be embodied have been shown herein, it is to be understood that the invention is not limited to any specific construction but may be embodied in various forms without departing from the spirit of the invention or the scope of the appended claims.

What is claimed is:

1. A mine comprising a detonator, a detonator circuit including a normally closed relay 19, a radio receiver having means to receive radiant energy, means controlled by said receiver in response to received energy to open said relay and thereby render said detonating circuit inoperative, said radio receiver comprising detector and amplifier means to receive, detect and amplify a radio wave modulated by at least three different signals, the frequency difference between any two of said signals being different selector circuits individually selective of the different signals, combining circuits having means to combine and obtain the beat frequencies between two pairs of said signals, a second combining circuit having means to combine said first beat frequencies and derive therefrom a secondary beat frequency, and means actuating said relay in response to energy of said secondary beat frequency.

2. A mine comprising a detonator, a detonator circuit including a normally closed relay 19, a radio receiver having means to receive radiant energy, means controlled by said receiver in response to received energy to open said relay and thereby render said detonating circuit inoperative, said radio receiver comprising detector and amplifier means to receive, detect and amplify a radio wave modulated by at least three different signals, the frequency difference between any two of said signals being different selector circuits individually selective of the different signals, combining circuits having means to combine and obtain the beat frequencies between two pairs of said signals, a second combining circuit having means to combine said first beat frequencies and derive therefrom a secondary beat frequency, a selector circuit selective of said secondary beat frequency, a detector circuit actuated by energy in said last selector circuit, said relay being actuated by said last detector circuit.

3. In combination, a mine having a detonator, a detonator circuit including a normally open relay and a normally closed relay in series, means responsive to the passage of a vehicle to close said normally open relay, an energizing circuit normally maintaining said normally closed relay closed, a radio receiver having an output circuit adapted to de-energize said energizing circuit for opening said last relay, said radio receiver being responsive to a carrier wave modulated by a plurality of different signals, and a vehicle borne transmitter having means to radiate a carrier wave modulated by said signals, whereby when said transmitter is operated even though the mine is approached by a vehicle, said radio receiver is energized to release said last relay and render said detonating circuit inoperative, whereas when said transmitter is inoperative and the mine is approached by a vehicle, said relays

are both closed to render said detonating circuit operative.

4. A radio receiver comprising detector and amplifier means to receive, detect and amplify a radio wave modulated by at least three different signals, the frequency difference between any two of said signals being different, selector circuits individually selective of the different signals, combining circuits having means to combine and obtain the beat frequencies between two pairs of said signals, a second combining circuit having means to combine said first beat frequencies and derive therefrom a secondary beat frequency, a selector circuit selective of said secondary beat frequency, a detector circuit actuated by energy in said last selector circuit, and a work circuit actuated by said last detector circuit.

5. A mine having a detonator, and means for operating said detonator including a pair of circuits and radio receiving means, said detonator operating-means requiring for its operation the energization, substantially simultaneously, of said two circuits, one of said circuits being energized by the approach of a moving metallic object, and the other of said circuits being under the control of said radio receiving means.

6. A mine having a detonator, means including a pair of relays, which, upon energization, are

adapted to set off said detonator, means adapted to normally maintain one of the said relays energized, additional means operative upon the approach of a moving metallic object to energize the other of said relays, and radio receiving means operative upon receipt of a pre-arranged signal to de-energize the normally energized relay.

7. A mine having a detonator, means including a pair of relays which, upon energization, are adapted to set off said detonator, radio receiving means adapted to energize one of the said relays upon receipt of a pre-arranged signal, and additional means adapted to energize the other of said relays upon the approach of a moving metallic object.

8. A mine having a detonator, and means for operating said detonator including a pair of circuits and radio receiving means, said detonator operating-means requiring for its operation the energization, substantially simultaneously, of said two circuits, one of said circuits being energized by the approach of a moving metallic object, and the other of said circuits being energized upon receipt by said radio receiving means of a pre-arranged signal.

JOHN HAYS HAMMOND, JR.
